UNITED STATES PATENT OFFICE

GIROLAMO BUZZONE, OF UPPER DARBY, PENNSYLVANIA

DESIGN FOR A RADIATOR SHELL

Application filed April 26, 1930. Serial No. 35,397. Term of patent 7 years.

To all whom it may concern:

Be it known that I, GIROLAMO BUZZONE, a citizen of the United States, residing at Upper Darby, in the county of Delaware and State of Pennsylvania, have invented a new, original, and ornamental Design for a Radiator Shell, of which the following is a specification, reference being had to the accompanying drawing, forming part thereof.

Figure 1 is a front elevational view of a radiator shell, showing my new design, and Figure 2 is a side elevation thereof.

I claim:

The ornamental design for a radiator shell as shown.

GIROLAMO BUZZONE.
